UNITED STATES PATENT OFFICE.

HUGH L. WARNER, OF DAYTON, OHIO.

COMPENSATING GEARING.

SPECIFICATION forming part of Letters Patent No. 732,327, dated June 30, 1903.

Application filed September 13, 1902. Serial No. 123,263. (No model.)

To all whom it may concern:

Be it known that I, HUGH L. WARNER, of Dayton, in the county of Montgomery and State of Ohio, have invented a new and useful Compensating Gear, of which the following is a specification.

My invention relates to improvements in what is known as "equalizing" or "compensating" gearing, and particularly the spur-gear type, through which two driven members, usually two axles, are made to turn with the same speed as the compensating gear, it being so made that when one axle revolves faster than the compensating gear itself the other axle revolves a corresponding amount slower. Thus it equalizes its own speed with the two driven axles.

The objects of my improvements are, first, to produce a compensating gear in which the various parts that are subject to wear can be made independent of each other; second, to produce a compensating gear that can be made and sold as a perfect compensating gear independent of how it is to be driven, whether by belt, chain, spur-gear, or otherwise; third, to produce a compensating gear that when fitted with such driver it need be nothing more than a rim attached to the outer periphery of my gear by any suitable means; fourth, to produce a compensating gear so constructed that the usual driver will readily interchange from one side to the other; fifth, to produce a compensating gear in which the driver, being a separate piece and wearing out much faster than any other part, may be taken off and a new one replaced without opening the working parts; sixth, to produce a compensating gear in which while in actual use the small pinions and their axles, which are liable to strains, can be taken out and examined or replaced independent of each other and independent of any other part, so as not to remove the entire gear for such purposes, and, seventh, to produce a compensating gear that has the strongest construction, most perfect alinement, most durable in wear, and economical to manufacture, all because of the one-piece frame, in which the pinions are independently set, perfectly

housed, properly separated, and self-contained and which also carries the two large spur-gears in perfect alinement and their retainers; and to accomplish these objects my compensating gear consists of the mechanism illustrated in the accompanying drawings, in which—

Figure 1 is a face view of my compensating gear, the axles removed, Fig. 2 is a sectional view taken, respectively, on a line A B, Fig. 1, the axles being shown in position. 60 Fig. 3 is a part of the driving member, the remainder broken away. Fig. 4 is a sectional view taken, respectively, on a line E F, Fig. 1, which shows how the pinions and their bearing-bolts are mounted in the frame. Fig. 65 5 is a section of the frame only, taken, respectively, on a line A C, Fig. 1, all parts removed. Fig. 6 is a face view of the frame only, all parts removed, showing the opening for the large spur-gear and openings for three pinions, a duplicate set of openings being in the opposite face. Fig. 7 is a face view of one of the retainers. Fig. 8 is a view of one pair of pinions and the two large spur-gears as they are in the frame. Fig. 9 is a side view 75 of a pinion bearing-bolt, the small end shown in section through center, so the internal thread can be seen.

Similar letters refer to similar parts throughout the several views.

My compensating gear consists, essentially, of a frame B, one or more pairs of pinions P, spur-gears E and F, bolts J, and retainers C, which when assembled may be mounted on two abutting axles, one spur-gear on each 85 axle, or in various other ways. I show in Fig. 2 the spur-gear F fastened on the solid axle G by the small key g, and the spur-gear E mounted on the hollow axle H, preferably brazed on; but I lay no broad claim to this 90 manner of mounting my gear.

My invention pertains rather to the construction of the compensating gear itself, in which the larger spur-gears E and F are journaled in the frame (see Fig. 2) by means of 95 the long hubs e^2 and f^2 and held in perfect alinement. These spur-gears are usually provided with outwardly-extending hubs e^3 and

f^3 , which may be used to fasten to. The outer radial face of the rim c^3 , which has spur-teeth c^4 , comes flush with the outer face of the web c . (See Fig. 2.)

5 The pinions L and M, arranged in pairs, are usually equally spaced around the spur-gears. The entire length of a single pinion is not quite as long as the width of the face of a spur-gear plus the space between the 10 spur-gears. (See Fig. 8) The pinions of each pair engage each other and engage the spur-gears, respectively.

15 The pinion bearing-bolt J (see Fig. 9) is preferably made of a single piece and has a large head j , with an extension of flange j^3 , which when in position, as in Fig. 2, performs three duties at once. First, it forms a dust-proof cover for the pinion L and holds it in place against the bottom m ; second, it 20 forms a rigid support for the outer end of said pinion, and, third, it holds the retainer C in place. The outer flange j^3 fits in against the shoulder b^{10} , Fig. 5, and prevents the bolt going in too far, so as to bind the pinion endwise. The small end of the bolt J is provided 25 with means for engaging the frame and for being locked fast. Said means is preferably the external and internal thread j^2 and o , one thread being a coarse right-hand and the 30 other a fine left-hand or otherwise.

35 The retainers C and D, Fig. 2, hold the spur-gears E and F in place, said retainers being held in place by a series of bolt-heads J, which engage the niches c^8 of the retainer C. (See Fig. 7.) The retainer C has a small flange c' around the outer periphery, which fits against the shoulder b^{11} , Fig. 5, and prevents it from going in too far and binding the large spur-gears.

40 The driving member A, which in the drawings is a sprocket-rim, (and which in practice may be something else,) is provided with teeth a^5 on its outer periphery for engaging a driving-chain, and inwardly-projecting lugs 45 a^2 , having counterbored holes a' , adapted to receive the screws a and forms a means for fastening the driver A on the frame B.

50 The frame B consists of three annular bands b^7 , b' , and b^4 , fastened together as follows: b^7 is of a smaller diameter than b' and is placed within it and joined to it by webs or spokes b^2 and pinion-cases b^{14} and b^{15} , and within b' is the third and smallest band b^4 , fastened to the band b' by the web b^3 , as seen in Figs. 1, 55 2, 5, and 6. The band b^4 is not so wide as the two outer bands b' and b^7 and has flanges b^5 and b^6 turned out on its bearing-box for the hubs e^2 and f^2 of the two spur-gears. The outer band b^7 has a series of inwardly-projecting lugs a^3 on one edge and a duplicate series a^4 on the opposite edge. These lugs 60 are preferably threaded to receive the screw a .

65 My compensating gear when assembled is very light and compact. As will be seen in Figs. 1 and 2, the adjacent ends of the hubs

e^2 and f^2 are in contact, while the outer periphery of said hubs fit snugly into the central bearing-box b^{16} . The inner radial faces of the spur-gear webs form bearings against the outer faces of the flanges b^5 and b^6 , and the overhanging rims c^3 are supported by the outer peripheries of the flanges b^5 and b^6 . The spur-gears are held in place by the retainers and the retainers by the pinion-bearing-bolt heads. The hollow spaces S and S' 70 75 are oil-chambers for grease or vaseline.

The peculiar construction of the pinion-cases b^{14} and b^{15} is such that with each pair of pinions in order to engage each other they 80 have to be inserted from opposite faces of the frame and run in individual cells almost completely incased and on independent bearing-bolts. Thus I am enabled to assemble my compensating gear independent of the driving 85 attachment.

Referring to Figs. 1 and 2, it is plain to be seen that if I want to remove an individual pinion or bearing-bolt I need only to remove the locking-screw O in the small end of the pinion bearing-bolt, removing the bolt and 90 pinion, and if I wish to examine the large spur-gears I need only remove the pinion bearing-bolts and the retainers, and the whole internal mechanism is exposed and may be withdrawn. Both faces of the frame B being 95 exactly alike, it is plain to be seen that the parts will interchange.

I am aware that prior to my invention compensating gears have been made in which a pair of spur-gears placed side by side and mounted on axles were respectively engaged by a pair of spur-pinions having hubs and said pinions engaging each other.

I therefore do not claim such a combination broadly; but

What I do claim as my invention, and desire to secure by Letters Patent, is—

1. In the frame of a compensating gear, the combination of an outer band, and an inner band connected to the outer band by spokes 100 or webs, and a central bearing-box connected to the inner band.

2. In a frame of a compensating gear, the combination of an outer band, an inner band, connections between the two bands, individual pinion-cases arranged in pairs and connected to the inner band, and a bearing-box in the center of the inner band, and a rigid connection between the two, substantially as described.

3. In the frame of a compensating gear, the combination of an outer band connected to an inner band, a central bearing-box connected to the said inner band, and individual pinion-cases arranged in pairs with the two 115 openings of each pair disposed in opposite directions, substantially as described.

4. In a compensating gear, the combination of an outer band and an inner band connected to the outer band, a central bearing- 120 125 130

box connected rigidly to the inner band, two spur-gears carried by the bearing-box one on either side thereof, and retainers fitted within the inner band for holding the spur-gears in position, substantially as described.

5. In a compensating gear, the combination of an outer and an inner band connected together, a central bearing-box connected to the inner band, a pair of spur-gears mounted within the inner band and having their inner hubs journaled in the said bearing-box, one or more pairs of pinions each pinion mounted in an individual case and each pair of pinions engaged with each other and respectively engaged with the spur-gears, substantially as described.

6. In a compensating gear, the combination of a frame having an outer band, an inner band, a central bearing-box, two spur-gears with the inner hubs journaled in said bearing-box, retainers substantially the same size as the spur-gears with projecting flanges thereon fitted inside the inner band, individual pinion-cases arranged in pairs and connected to said inner band, pinions mounted within said cases, and bearing-bolts which go through said pinions and engage the bottoms of said pinion-cases and are provided with heads of sufficient size to cover the ends of the pinions and form rigid bearings for their outer ends, substantially as described.

7. In a compensating gear, the combination of a frame having in each face a like series of individual pinion-openings with bottoms to said openings, and each opening adapted to receive a spur-pinion, a spur-gear in the center of each face, and a pinion inserted in each opening substantially as described.

40 8. In a compensating gear, the combination of a frame having in both faces thereof, a like series of openings with bottoms, and an individual gear or pinion inserted in each of said openings, and individual retainers which form covers for each individual gear or pinion substantially as described.

9. In a compensating gear, the combination of a frame with two spur-gears in axial alinement, one or more pairs of pinions, said pinions engaged with each other and respectively engaged with the spur-gears, retainers holding the spur-gears in place, and pinion bearing-bolts forming axles for said pinions and having heads of sufficient size to cover the ends of said pinions and also to engage the retainers covering the spur-gears holding them in place, said heads and said retainers being flush with the frame-faces, all substantially as described.

60 10. The combination in a compensating gear, of a frame carrying spur gears and pinions, with spur gears and pinions mounted therein, each gear and pinion having an individual peripheral wall almost completely encircling it, and an individual covering or

retainer for each of said spur gears and pinions.

11. The combination in a compensating gear, of a frame with a series of hubless spur-pinions carried therein and arranged in pairs and mounted on detachable bearing-bolts, said bolts having large heads individually covering said spur-pinions, the two pinions of each pair engaging each other substantially one-half their entire length, substantially as described.

12. The combination in a compensating gear, of a frame having a series of like individual pinion-sockets in both faces thereof, each socket provided with a bottom substantially flush with the inner face of the rim of the spur-gear on the opposite side, with two driven spur-gears, each of said gears having their inner hubs journaled in a central portion of said frame, pinions carried in said sockets and means for individually covering, holding and forming a bearing for said pinions, substantially as described.

13. The frame B composed of bands having individual pinion-cases $b^{15} b^{15} b^{15}$, opening on one face and $b^{14} b^{14} b^{14}$, opening on opposite face, substantially as shown and for the purpose specified.

14. The combination in a compensating gear, of a circular frame having a central opening through it and a series of pinion bearing-bolts independent of each other and each bolt having a large head, said bolts arranged in pairs with their axes substantially parallel with each other and the central opening, and bolts of each pair having their heads in opposite directions, substantially as described.

15. The retainer C, having niches $c^8 c^8 c^8$ in its outer periphery, said niches having shoulders c^2 , and the central opening c^9 , substantially as shown, for the purpose specified.

16. The hubless pinions L and M and the spur-gears E and F, engaging each other, detachable bearing-bolts having large heads completely covering the ends of said pinions, means for supporting said gearing, substantially as shown, for the purpose specified.

17. The combination in a compensating gear, of an open frame with inclosed spur-gearing and each of said gears in an individual socket, and an independent driving member detachably secured to the outer band of said frame, substantially as described.

18. In a compensating gear, the combination of two spur-gears with the frame, each gear having its inner hub journaled in the central bearing-box of the frame, said bearing-box provided with flanges forming a support underneath the projecting rim of the spur-gears and forming a bearing against the inner face of the webs of both spur-gears, substantially as described.

19. A compensating-gear frame composed of bands, the outer one having two series of

lugs projecting inwardly, one series on either side thereof.

20. In a compensating gear, the combination with the frame having a central bearing-box, of two spur-gears in axial alinement and having their adjacent hubs rotatively mounted in said bearing-box, and detachable frame members substantially the same size as said

spur-gears, said members serving as retainers and bearings to keep said spur-gears in place. 10

In witness whereof I subscribe my signature in presence of two witnesses.

HUGH L. WARNER.
